pany, Kenosha, Wis., a corporation of Wis-
consin

Application December 31, 1949, Serial No. 136,184

15 Claims. (Cl. 45—24)

1

This invention relates to a curtain stretcher and more particularly relates to a curtain stretcher of relatively small size and light weight, which is of particular utility where space is limited.

It has long been common to construct curtain stretcher frames of wood and to drive curtain impaling pins into the wood with a portion of the shank having a sharpened end projecting therefrom so that the curtains may be impaled or secured thereon. Wooden stretchers have been heavy and unwieldy and the wood has been affected adversely by atmospheric changes so that the pins loosen and eventually fail to properly secure curtains or other fabrics.

It is accordingly an object of this invention to provide a curtain stretcher of light weight metal which is much easier to handle than the previous heavy wooden ones.

It is a further object of my invention to provide such a curtain stretcher in which the impaling pins are secured directly in the metal so that they will not be loosened by climatic or atmospheric changes, as is the case with wooden stretchers.

It has generally been the practice to construct curtain stretchers of rather large size so that a curtain may be secured on one side of the stretcher. This is very undesirable when space is a limiting factor, such as in an apartment or a small house. I have, therefore, proposed to construct a curtain stretcher of comparatively small size with a relatively wide inverted U-shaped channel at the top so that a part of the curtain may be secured on one side of the stretcher and a part on the other side, the curtain being folded over the top of the stretcher. The light weight metal of which the stretcher is constructed is noncorrosive and will not mark curtains or be damaged by the moisture from the curtains as would other materials such as wood or iron.

Thus, it is an object of the present invention to provide a curtain stretcher of comparatively small size having an inverted U-shaped channel at its top so that a relatively large curtain may be hung over it and secured on both lower sides of the curtain stretcher.

It is desirable to be able to dry curtains of various sizes on a single curtain stretcher. Stretchers have been provided in the past with a vertically shiftable, horizontal curtain securing member and a horizontally shiftable upright curtain securing member in addition to the uprights at each end of the curtain stretcher to secure a curtain

2

along a vertical or substantially vertical edge. The addition of this extra upright member has, of course, added to the cost of the curtain stretcher and deprived many potential users of its benefits thereby, and has additionally added to the weight and unwieldiness of the curtain stretcher.

It is an object of the present invention to obviate these last named difficulties by the provision of a curtain stretcher having only two upright members on each side, these members being foldable so that the curtain stretcher may be stored in a small space.

A more specific object of my invention is to provide a curtain stretcher as outlined in the foregoing paragraphs in which moving the legs into an operative position automatically clamps them in place.

A further object of this invention is to provide a relatively small light weight curtain stretcher in which bridge members are provided to make it unnecessary for a curtain or the like to be secured to securing members in planes spaced considerably from one another at the intersections of said members.

It is a further object of a modified form of the invention to provide means for securing hemmed edges of a curtain or the like without the necessity of piercing or clamping the fabric.

Occasionally it is desirable to dry a curtain of unusually large size such as those used on the large picture windows currently in vogue. Such curtains as well as large table cloths and blankets may run as large as 90 inches by 144 inches. It would be possible to provide a stretcher of large enough size to accommodate such large pieces of material but such a stretcher would be unwieldy and uneconomic since the great majority of curtains and other fabrics to be dried are much smaller.

It is therefore an object of this invention to provide a curtain stretcher which may be extended to accommodate fabrics of practically any size.

The foregoing and other objects and advantages will be apparent upon reading the following description when taken in conjunction with the accompanying drawings in which:

Fig. 1 is a perspective view of a curtain stretcher embodying my invention;

Fig. 2 is an end view with the legs in partially folded or unclamped position;

Fig. 24 is an enlarged plan view of a portion of the stretcher shown in Fig. 17.

Figs. 1—3 show general views of my curtain stretcher. The curtain stretcher includes a relatively wide, U-shaped, longitudinal top member or ridge pole 20 of light weight metal such as aluminum and having inwardly and upwardly turned flanges 22 and 24, respectively, as may best be seen in Figs. 5, 7 or 8. Two pairs of legs 26 and 28 of the same material as the ridge pole 20 are secured thereto in a manner to be described in detail later, and are shown at opposite ends of the member 20 in Fig. 1 in which position they are spaced as far apart as possible in order to receive a wide curtain. Foldable bracing members 30 and 32, which may be of a well-known type, locking in open position, are pivotally joined to the legs 26 and 28, respectively, to secure the legs in spread-apart position as shown in Fig. 1. The bracing members fold as 33 in Fig. 2 so that the pairs of legs as 26 in Fig. 2 may be brought substantially into juxtaposition preparatory to complete collapsing of the stretcher for storage. Vertically adjustable horizontal members 34 and 36 of the same light weight metal as the ridge pole 20 are secured to the legs 26 by clamps 38 and 40 and to the legs 28 by bridge clamps 42 and 44, as will later be described in greater detail.

As best seen in Figs. 2 and 3, the legs 26 may be folded inwardly toward one another and upwardly against the ridge pole 20 for storage purposes. The legs 28 may also be folded toward each other, but preferably not in such close juxtaposition as the legs 26, so that the legs 28

may be folded inwardly toward the top member 20 and in so doing straddle the legs 26, it being understood that the position of the legs 26 and 28 may be reversed.

Prior to folding the legs 26 and 28 upwardly, the horizontal members 34 and 36 are, of course, removed by loosening the clamps 38 and 40 and the bridge clamps 42 and 44. The inner edge of each of the legs 26, 28 and the upper edge of each of the horizontal members 34, 36 are provided with curtain impaling pins 37, which are preferably ball pointed as disclosed in my co-pending application, Serial No. 91,130, filed May 3, 1949, and are secured in a manner readily seen in Fig. 10. In Fig. 10 one of the legs 26 is shown and has a cross section which is similar to the cross section of the legs 28 and the horizontal members 34, 36. The leg has an essentially channel-shaped portion generally designated as 46, this portion providing longitudinal strength, and an extending portion 48 to secure a metal impaling pin which is harder than the light weight metal which comprises the greater part of the curtain stretcher. The specific details of the mounting of the pins are disclosed in my co-pending application, Serial No. 94,675, filed May 21, 1949.

It is desirable to be able to move the legs 26 and 28 relatively toward and away from each other so that curtains of various widths may be secured, as suggested at an earlier point as one of the objects of this invention. As a curtain is to be stretched across the top of the member 20, there must be no portions projecting above it. Accordingly, I have devised means not only for securing the legs 26, 28 to the under side of the top member 20 but have devised means whereby the legs are automatically locked in operative position when they are folded away from each other. These means are illustrated in detail in Figs. 5—8. The legs 26 have secured at their upper ends members 50 and 52 which are essentially of a double L-shape. These members act as levers in the locking action and are sometimes hereinafter referred to as "levers." These members may be secured to the legs by any desirable means such as rivets 54. The members 50, 52 are provided with apertures 56 adjacent their upper inner extremities through which a threaded bolt 58 is passed. An inverted channel-shaped locking member 60 having horizontally extending wings 62 and 64 is provided with an aperture 66 through which the bolt 58 also passes. The wings 62, 64 of the locking member 60 may have material removed as at 68, 70 in order to decrease the weight of the curtain stretcher and conserve material. The bolt 58 has a coiled compression spring 72 interposed between its head and the member 60 and has a nut 74 which may conveniently be a wing nut threaded on its opposite end. The rivets 54 pivotally secure the legs 26 to the members 50 and 52 and each of these members is provided with a tab 76 and 77 struck outwardly from the body of the member to stop the legs in their proper downwardly extending position as may be seen in Fig. 6. Headed rivets 78 and 79 are secured in the members 50 and 52 adjacent the tops of the legs 26 so as to frictionally engage the legs and secure them in open position.

The locking member 60 is slid into the end of the longitudinal top piece 20 and tabs 80 struck out from the inturned flanges 22 are bent upwardly to prevent the accidental removal of the member 60. The spring 72 is fitted over the bolt 58 and the bolt is placed in the aperture 66 prior

to the insertion of the member 60 in the top piece 20. Either before or after this insertion the members 50 and 52 are placed over the bolt 58 as shown in Fig. 7 and the nut 74 is threaded onto the end of the bolt 58. With the members 50 and 52 folded toward each other in Fig. 7, the member 60 is held out of contact with the inturned flanges 22 by the uppermost portion of the lever 50. The levers 50, 52 and the legs 26 to which they are attached may thus be moved longitudinally relative to the top piece 20 so that any width curtain can be accommodated. When the legs are properly located for any given curtain, they are merely spread apart to the position shown in Fig. 5. The members 50, 52 act as levers to pull down against the nut 74 and hence on the bolt 58. This causes the spring 72 to be compressed and forces the locking member 60 downward against the flanges 22 so that the flanges are clamped between the flanges 62, 64 and the member 60 and corners of the double L-shaped members 50, 52, and the legs are locked in position and no longer move longitudinally of the top piece 20.

The legs 26, 28, as previously mentioned, are of light weight material and are preferably formed by bending sheet material, although it may be possible to extrude them. To prevent damage to a floor or other supporting surface by the inherently sharp edges at the lower ends of the legs, I have provided feet 82 which are best seen in Figs. 6 and 9. These feet are preferably formed of an essentially horseshoe-shaped strip of rubber or rubber-like material folded over the bottom edge of each leg 26, 28 and secured by a rivet 84 extending through the extremities of the rubber foot and through an aperture 86 in the bottom of the leg.

Each of the horizontal curtain securing members 34, 36 has a cross section similar to that of the legs 26, 28 and has a row of impaling pins 88 secured along its upper edge in a manner similar to the impaling pins 37 on the legs 26, 28. Each of these horizontal members is secured to the legs 26 by a clamp 38, 40 as shown in Fig. 1. These clamps are of similar construction although in relatively inverted positions, and consequently a description of one will serve for both. Fig. 10 shows the clamp 40. The clamp comprises a longitudinal portion 90 which is also shown in Fig. 13, this portion being channel-shaped transversely for stiffness and substantially L-shaped longitudinally. The L-shaped portion 90 is secured to the horizontal member 36 by any suitable means such as rivets 92. A second portion of the clamp 40 is an essentially J-shaped member 94. One upstanding portion of the J-shaped member is slotted as at 96 to receive the L-shaped member 90, and the other upstanding portion of the member 94 is apertured as at 98 to receive a threaded bolt 100, which has a square portion adjacent its head and is also passed through a square aperture 102 in the transversely extending portion of the L-shaped member 90. A coiled spring 104 is interposed between the members 90 and 94 and is located about the shank of the bolt 100 so as to normally force the member 94 away from the horizontal member 36. A wing nut 106 threaded on the bolt 100 opposes this force. The J-shaped member 94 is provided at a corner, 70 which is the lower right corner in Fig. 10, with a shoulder portion 108 formed by a loop in the metal. An anti-friction grommet 110 is secured in the upstanding portion of the J-shaped member 94 adjacent this shoulder. As is best seen 75

in Fig. 10, tightening of the wing nut 106 on the threaded bolt 100 clamps the leg 26 between the grommet 110 and the end of the horizontal member 36 to prevent vertical motion while the shoulder 108 prevents the clamp 40 from being disengaged from the leg 26 by a force tending to move it transversely thereof. If it is desired to move the member 36 vertically, it is only necessary to partially unscrew the wing nut 106, which allows the spring 104 to force the J-shaped member 94 to the left and loosen the clamping action.

The end of the horizontal member 36 secured to the leg 26 by the clamp 40 has its curtain impaling surface lying in the same plane as the curtain impaling surface of the leg 26. It is apparent, however, that if the legs 26, 28 are to be movable toward and away from each other that some other means must be provided for securing the opposite end of the member 36, and at this point of securing the curtain impaling surfaces of the member 36 and leg 28 would lie in different planes, which would of course tend to pull the curtain away from one of the groups of impaling pins. To obviate the difficulties engendered by this situation, I have provided a bridge clamp 44. The bridge clamp 42 securing the horizontal member 34 to the other leg 28 is similar and need not be described in detail. As shown in Figs. 11, 12 and 14, the bridge clamp 44 includes a U-shaped member 112 having inturned flanges 114 at its upper extremities. As may best be seen in Fig. 12, the dimensions of the U-shaped member 112 are such that it fits snugly over the horizontal member 36. The bight of the U-shaped member 112 is provided with a square aperture 116 which receives a threaded bolt 118 having a square portion adjacent its head cooperable with the aperture 116 to prevent rotation of the bolt. A clamping member 120, which is in part channel-shaped in cross section for rigidity fits over the bolt 118 with a coiled spring 120 interposed between it and the U-shaped member 112 so as normally to force the clamping member away from the member 112. A wing nut 122 is threaded onto the bolt 118 to oppose the force of the spring. The forwardly extending portion of the clamping member 120 fits over the leg 28 and is provided with a short inturned flange 124 to preclude disengagement of the leg 28. The opposite or butt end of the clamping member 120 is provided with a flange portion 126 which bears against the front surface of the horizontal member 36 so that the horizontal member 36 may be securely clamped to the leg 28 by advancing the wing nut 122.

Besides the clamping portions just described, the bridge clamp 44 is provided with a bridge portion 128. The bridge portion includes a substantially straight, longitudinal member 130 secured at one end to the bight of the U-shaped member 112 as by a rivet 129 and provided at its opposite end with an integral inturned finger 132 which bears against the front surface of the back portion of the horizontal member 36. A curtain impaling section 134 similar to the back surface 48 and pin securing portion of the leg 26 as shown in Fig. 10 is secured to the longitudinal member 130 by any suitable means, such as rivets 136. The impaling pins 138 in the section 134 thus allow the junction between the horizontal member 36 and leg 28 to present means for meeting the curtain from one curtain securing plane to another curtain securing plane without an abrupt jump or break. It is to be understood that the bridge portion of the clamp could consist of

but a single piece rather than the longitudinal member 130 and section 134. To prevent the accidental movement of the bridge clamp 44 from the end of the horizontal member 36, I have provided a button headed rivet 139 as shown in Figs. 11 and 12, the head of which acts as a stop against one leg of the U-shaped member 112.

In Figs. 4, 15 and 16, I have shown a modification of my invention in which it is unnecessary to pierce the curtain fabric along two of the edges. Horizontal rectangular bars 34a and 36a having a rectangular cross section are slipped through the hems at either end of the curtain. The hem is shown as 140 in Fig. 16. To secure the bar 36a in position, I have provided a securing member 142. Although the securing member described is the one appearing on the front leg 26 in Fig. 4, it is apparent that this description is sufficient as the other securing members are similar. The securing member 142 includes a U-shaped member 144 having inturned flanges 146 at the upper extremities of the legs of the U, and is suitably dimensioned to encompass the leg 26 in a manner similar to that in which the member 112 of the bridge clamp 44 engages the horizontal member 36. The bight of the U is provided near one side with a square aperture through which a threaded bolt 148 is passed. The bolt is provided with a square portion adjacent its head to prevent rotation in the U-shaped member 144. A clamping member 150 substantially in the shape of the blocked letter S is apertured and placed over the bolt 148 as seen in Figs. 15 and 16. A coiled spring 152 is interposed between the clamping member 150 and the U-shaped member 144 normally to force the clamping member away from the leg 26. A wing nut 154 threaded onto the bolt 148 opposes the force of this spring and clamps the clamping member 150 against the leg 26 in a vertically adjusted position to secure the rod or bar 36a, which fits within the top portion of the S-shaped clamp where it is held in place by the stretching curtain.

In Figs. 17-23 I have shown a modification of my invention which is adapted to stretch curtains or other fabrics of great size by means of extensions to be connected to the basic curtain stretcher heretofore described. In these figures certain of the parts are identical with those previously disclosed and these parts are identified by similar numerals with the addition of a distinguishing subscript.

The curtain stretcher shown in perspective in Fig. 17 embodies the ridge pole 20a having inwardly and upwardly directed flanges 22a and 24a respectively taken from the stretcher shown in Fig. 1. Two pairs of legs 26a and 28a are secured to the ridge pole 20a in a manner similar to that previously described. Foldable bracing members 30a and 32a maintain the legs in spread apart position. Vertically adjustable horizontal members 34a and 36a are secured to the legs 26a by clamps 38a and 40a. In order to present a stretcher of greater length a second ridge pole 20b similar to the ridge pole 20a is joined to the latter by means of a curved wooden bar 156 fitting within the ridge poles 20a and 20b. The lower surface of the bar or rod 156 is provided with longitudinal slots 158 which accommodate the upwardly turned flanges 22a of the ridge pole 20a and the similar flanges of the ridge pole 20b. Auxiliary bracing legs 160 are joined to the composite ridge pole at the junction of the ridge poles 20a and 20b. The primary function of

these legs is to support the center of the ridge pole and accordingly the legs are substantially channel shaped (Fig. 23) and are not provided with curtain securing pins. The structure for securing auxiliary legs is similar to that used for securing the end legs and comprises (Fig. 18) double L-shaped members 50c and 52c pivotally secured to the legs by means such as rivets 54c. A threaded bolt 58c extends through the bar or rod 156 which is bored and countersunk to receive the bolt and its head. The head may be non-circular to cooperate with the countersunk aperture receiving it to prevent rotation of the bolt or rotation may be prevented in any other desirable manner. A wing nut 74c is threaded on the end of the bolt in order to draw the levers or members 50c and 52c upward to lock the auxiliary legs in position, the auxiliary legs being held in spaced apart relation by foldable brace members 162 similar to those previously described.

Additional height for the stretcher is provided by extending leg members attachable to each of the legs and auxiliary legs. The extending leg members 26d, 28d, and 160d are identical in cross section with the legs to which they are secured and the leg extension 26d and 28d are provided with curtain securing pins 31d along their inner edges.

In Fig. 20 a connection is shown between one of the legs 26a and an extension 26d and it is to be understood that the connection between the other leg 26a and extension 26d and the legs 28a and 28d are similar. The extension includes a channel shaped splicer 164 fitting within the channel shaped portion 46a and 46d of the leg and extension. A threaded bolt 166 extends transversely through the flanges of the splicer 164 and may be provided with a non-circular portion beneath its head to prevent rotation. A clamping member 168 which is substantially channel shaped overlies the front portion of the channel shaped leg portions 46a and 46d and is clamped against them by a wing nut 170 threaded on the bolt 166 to lock the leg 26a and extension 26d between the splicer 164 and clamping member 168. Rubber feet 82d are provided on the bottoms of the leg extensions 26d and 28d to prevent marring of the floor or other supporting surface.

The auxiliary leg extensions 160d present the same cross section as the auxiliary legs 160 but are smaller so that they fit within the auxiliary legs 160. Both the auxiliary legs and extensions are apertured in a plurality of places to receive a threaded bolt 170 having a wing nut 172 which locks a clamp 174 (Figs. 18 and 19) against the leg extension and leg to secure them rigidly in adjusted connection. The auxiliary leg extensions are also provided with rubber feet 82d. The horizontal members 34a and 36a are extended by means of similar members 34e and 36e which are secured to the legs 28a by bridge clamps 42a and 44a. The members 36a and 36e are connected as shown in Figs. 23 and 24 by means of a channel shaped splicer 176 and a clamping member 178 similar to those used in securing the legs and leg extensions together. A threaded J-shaped bolt 178 extends through the webs of the splicer 176 and through the clamping member 178 while having a portion looped about the leg extension 160d to securely clamp the two horizontal portions together against the leg extension under the action of wing nut 180. The

horizontal members 34a and 34e are secured in the same fashion.

It is apparent that I have herein presented a curtain stretcher which is extremely light in weight and is adapted to secure curtains which are large compared with its over-all dimensions and which is readily foldable so as to occupy a very small storage space. It is also apparent that my improved curtain stretcher is adapted to hold any size curtain up to about twice the size of the stretcher and has a minimum of adjustable parts, some which automatically clamp in place upon the unfolding of the stretcher. The stretcher, although made of metal rather than the conventional wood, will not mar or otherwise harm surfaces about which it is placed and will not be affected by the dampness of a curtain being stretched, and the impaling pins are secured in the metal in such a manner that they cannot become loose with age, with the extensions provided a fabric piece of any practical size can be stretched. Although I have referred to the stretcher throughout as constructed of metal, I contemplate that it could be formed of plastic sheet material.

Although I have shown and described certain preferred embodiments of my invention, it is to be understood that these are for illustrative purposes, only, and that I intend my invention to include all that may fall fairly within the spirit and scope of the appended claims.

I claim:

1. A curtain stretcher comprising a pair of horizontally spaced, upright frame members having relatively diverging legs, a pair of vertically adjustable horizontal metal frame members carried by said upright frame members, a ridge pole overlying the upper ends of said upright frame members and extending between and interconnecting said upright frame members, said ridge pole being formed of metal and substantially in the shape of an inverted U with said legs substantially tangent thereto whereby a curtain may be stretched across it without creasing the curtain, and rows of fastening devices disposed on some of said frame members for holding marginal portions of a curtain upon the respective frame members.

2. A curtain stretcher comprising a pair of horizontally spaced, upright frame members having relatively diverging legs, a pair of vertically adjustable horizontal frame members of sheet material carried by said adjustable frame members, a ridge pole extending between and interconnecting said upright frame members and overlying the upper ends thereof, said ridge pole being formed of sheet material and substantially in the shape of an inverted U with said legs substantially tangent thereto whereby a curtain may be stretched across it without creasing the curtain, and rows of fastening devices disposed on some of said frame members for holding marginal portions of a curtain upon the respective frame members.

3. A curtain stretcher comprising a pair of horizontally spaced upright frame members, each such upright member including a pair of legs of sheet material hinged to securing members at their upper ends, a pair of vertically adjustable horizontal frame members of sheet material, a smooth top piece of sheet material formed transversely as a continuous smooth curve extending across and entirely overlying the top of said upright frame members, means for securing said top piece to the upper ends of said securing mem-

bers with said legs extending substantially tangentially to said top piece, fastening devices disposed on said upright members for holding edge portions of a curtain, said horizontal frame members being adapted to secure edge portions of a curtain, and means for adjustably securing said horizontal frame members to said upright frame members.

4. In a curtain stretcher a pair of upright legs foldable to and from each other, a ridge pole having a longitudinal hollow portion and means secured to the top of said legs and fitting within the hollow portion of said ridge pole and actuated by folding said legs away from one another for securing said legs to said ridge pole.

5. In a curtain stretcher a pair of upright legs, a substantially hollow ridge pole, lever means secured to the top of said legs and a locking member carried within the hollow portion of said ridge pole, said locking member being pulled into frictional engagement with said ridge pole by folding said legs away from one another to preclude movement of said legs longitudinally of said ridge pole.

25 6. In a curtain stretcher, structure as defined in claim 5 in which a part of said hollow ridge pole is clamped between the locking member and the lever means.

7. In a curtain stretcher a pair of upright metal legs, a metal ridge pole in the form of an inverted U and having inturned flanges at its lower end, a metal locking member carried within said ridge pole, and metal lever means secured to the top of said legs, said lever means acting on said locking member upon folding of said legs away from each other to clamp said inturned flanges between said locking member and said lever means.

8. A curtain stretcher comprising a pair of 40 metal upright members, a pair of metal horizontal members, a metal ridge pole extending between said upright members, said ridge pole being in the shape of an inverted U and having inturned flanges at the extremities thereof, means connecting said upright members to said ridge pole for relative horizontal adjustment to vary the spacing of said upright members, both of said horizontal members being adapted to hold the ends of a curtain to be stretched with the intermediate portion of the curtain folded over said ridge pole, fastening means on said upright members for securing the edges of the curtain to be secured, and adjustable means connecting said horizontal members to said upright members.

50 9. A curtain stretcher comprising a pair of metal upright members, a pair of metal horizontal members, a metal ridge pole extending between said upright members, said ridge pole being in the shape of an inverted U and having inturned longitudinal flanges, a locking member carried within said ridge pole and brought into frictional engagement with said longitudinal flanges by folding of said upright members, said horizontal members being adapted to hold the ends of a curtain to be stretched with the intermediate portion of the curtain folded over said ridge pole, and fastening means on said upright members to secure the edges of the curtain to be stretched.

70 10. A curtain stretcher as set forth in claim 9 in which lever means are provided at the top of the upright members and actuate the locking members to clamp the longitudinal flanges between the locking member and the lever means upon unfolding said upright members.

11

11. A curtain stretcher comprising a pair of horizontally spaced upright metal frame members, an upper metal ridge pole extending between said upright frame members, means interconnecting said upright frame members with said ridge pole to permit relative horizontal adjustment thereof, said means including pivotable means whereby said upright frame members can be folded into juxtaposition with said ridge pole for storage, a pair of horizontal metal frame members extending between said upright frame members and adjustably and detachably secured thereto for the accommodation of different size curtains and for removal when said curtain stretcher is to be stored, said horizontal frame members and said upright frame members being adapted to secure edge portions of a curtain to be stretched.

12. A curtain stretcher as set forth in claim 11 in which clamping bridge means adjustably secure the horizontal frame members to some of the upright frame members to provide a smooth junction between said members.

13. A curtain stretcher comprising a plurality of horizontally spaced upright frame members including hingedly connected diverging legs, a plurality of additional members securable to said upright members to extend longitudinally therefrom, a plurality of top frame members extending between and interconnecting said upright frame members, said top frame members having adjacently disposed longitudinally hollow ends, means for securing said top frame members to one another including a member fitting within said hollow ends, a plurality of horizontal frame members spaced below said top frame members and carried by said upright frame members, means on at least some of said diverging legs for clamping said top frame members and said securing member together upon diverging movement 40 of those legs, and fastening devices disposed on

12

some of said frame members for holding a curtain upon the stretcher.

14. A curtain stretcher comprising a plurality of horizontally spaced upright frame members having diverging legs, a plurality of vertically adjustable horizontal metal frame members carried by said upright frame members, a ridge pole extending between and interconnecting said upright frame members and entirely overlying the upper ends thereof, said ridge pole being formed of metal and presenting a smooth surface convex upwardly with said legs substantially tangent thereto whereby a curtain may be stretched across said ridge pole without creasing the curtain, an extensible member for at least one of said ridge poles, upright frame members, and horizontal frame members, and means for securing said extensible members in extending position.

15. A curtain stretcher as set forth in claim 14 in which the ridge pole, upright frame members, and horizontal frame members all have longitudinally hollow ends, the extensible member has a longitudinally hollow end and the means for securing said extensible member includes a member fitting within at least a pair of said hollow ends.
